CLAIM

The ornamental design for an aromatherapy pillow, as shown and described.

DESCRIPTION

FIG. 1 is a perspective view of an aromatherapy pillow, taken from the bottom and right side, showing our new design;

FIG. 2 is a front elevational view thereof;

FIG. 3 is a left side elevational view thereof taken from FIG. 1, the right side view being the same;

FIG. 4 is a back plan view thereof;

FIG. 5 is a top plan view thereof;

FIG. 6 is a bottom plan view thereof; and,

FIG. 7 is a perspective view of an aromatherapy pillow, taken from the left side showing our new design in an alternate position.
